UNITED STATES PATENT OFFICE

HERMENEGILDO C. REYES, OF MANILA, PHILIPPINE ISLANDS

ROOF ANCHORING MEANS

Application filed October 23, 1929. Serial No. 401,812.

This invention appertains to a novel device for anchoring galvanized iron or similar metal roofing in proper position on a building and has for one of its primary objects to provide a novel wire fastening device which will effectively engage the roofing material and the roof rafters so as to effectively hold the roofing material in proper position and against displacement incident to high winds and the like, and which will permit the roofing to be placed in position on a building in a minimum amount of time without undue labor and expense.

Another important object of my invention is the provision of a wire fastening device for metal roofing embodying a bendable shank portion for insertion through the roofing material and having a concavo-convex head carried by one extremity thereof for engaging the outer face of the roofing material, the wire shank constituting means for engaging anchoring members such as nails driven into the roof rafters.

A further object of my invention is the provision of a wire fastening device for anchoring roofs in place embodying a straight shank portion for insertion through the roofing material having a concavo-convex head at one end for engaging the exterior face of the roofing material and a substantially U-shaped loop at its inner end for engaging over an anchoring member such as a nail driven into the roof rafters, the loop constituting means for straddling the anchoring member and for permitting the fastener to be wound thereabout.

A still further object of my invention is to provide an improved wire fastening device for metallic roofing of the above character, which will be durable and efficient in use, one that will be simple and easy to manufacture, and one which can be placed upon the market at a reasonable cost.

With these and other objects in view, the invention consists in the novel construction, arrangement and formation of parts as will be hereinafter more specifically described, claimed, and illustrated in the accompanying drawing, in which drawing:

Figure 1 is a fragmentary perspective

view showing several of my wire fasteners in use;

Figure 2 is a side elevation of one of my improved fasteners with the head thereof in section;

Figure 3 is a fragmentary side elevation of a modified form of one of my fasteners showing the head formed integral with the shank;

Figure 4 is a top plan view of the modified form;

Figure 5 is a diametric section through the head of the modified form of the device, and

Figure 6 is a fragmentary side elevation of a still further modified form of my invention showing the head thereof in diametric section.

Referring to the drawing in detail, wherein similar reference characters designate corresponding parts throughout the several views, the letter A generally indicates one form of my improved roof fastening device which is adapted to be associated with a galvanized iron roofing B or similar roofing. As shown in Figure 1, the galvanized roofing B is laid upon the roof rafters C and my improved device A constitutes the means for rigidly connecting the roofing B with the rafters.

As shown in Figures 1 and 2, my improved device A comprises an elongated shank 10 preferably formed of wire having its lower end bent back upon itself in spaced relation to form a parallel leg 11. The leg 11 and the shank 10 constitute an open loop, for a purpose which will be later described. The upper end of the shank 10 receives a concavo-convex or dish-shaped washer 12 and the upper end of the shank can be upset and soldered thereto, as at 13, for permanently securing the head 12 to the shank. The shank 10 and the head 12 can be formed of galvanized material if so desired.

In use of my invention, the shank 10 is inserted through suitable openings formed in the roofing material B until the head 12 comes into contact with the outer face of the roofing material and the loop 11 is placed over a suitable anchoring member such as a nail 15 driven into the roof rafter C. The leg 11 can now be coiled about the nail 15 which will

draw the head 12 into intimate contact with the outer face of the roofing material. This constitutes an efficient means for anchoring the roof B in place and prevents the roof from being blown off of the rafters during a high wind. Further, the means is of an exceptionally simple and durable character and will permit the roofing B to be connected to the rafters C in a minimum amount of time and with the expenditure of a minimum amount of labor.

Modified forms of heads can be provided for the shank 10 and in Figures 3 to 5 inclusive I have shown one modification. In this form the upper end of the shank 10 can be bent back upon itself as at 16 and coiled as at 17 to provide a substantially conical or concavo-convex shaped head. The convolutions of the wire gradually increase in diameter as clearly shown in the drawing and these convolutions are preferably drawn into intimate contact with one another. In this form of the invention the head is placed into engagement with the outer surface of the roofing B, as in the form previously described, and the convolutions 17 will be drawn into intimate contact with one another and with the roof upon the winding of the inner end of the wire about the nail 15. In this form, the material from which the shank and head is formed can also be galvanized.

In Figure 6 of the drawing I have illustrated a further modified form of the invention in which I have provided a dish shaped washer head 20 for engaging the roofing material and the shank 10 of the fastener is inserted through the axial center of the head and can be provided with a nail head 21 at its upper end for engaging the outer surface of the head 20. This form of the invention is used exactly the same as the forms above described.

Changes in details may be made without departing from the spirit or the scope of this invention, but

What I claim as new is:

An anchoring device for metal roofs comprising an elongated shank formed of bendable material, and an integral coiled substantially concavo-convex shaped head formed on the upper end of the shank, the convolutions of the coil lying in different planes increasing in diameter toward the free edge of the head and being in intimate contact with one another, said elongated shank being adapted to be wound around a fastening member at its lower end for permitting a free movement under expansion and contraction of an element adapted to be anchored thereby.

In testimony whereof I affix my signature.
HERMENEGILDO C. REYES.
